United States Patent Office

WILLIAM M. MILLER, OF TULPEHOCAN, PENNSYLVANIA.

Letters Patent No. 66,083, dated June 25, 1867.

IMPROVED MEAT-CUTTER.

The Schedule referred to in these Letters Patent and making part of the same.

TO ALL WHOM IT MAY CONCERN:

Be it known that I, WILLIAM M. MILLER of Tulpehoccany, in the county of Berks, and State of Pennsylvania, have invented a new and useful improvement in Meat-Cutters; and I do hereby declare the following to be a full, exact, and clear description of the same, reference being had to the accompanying drawings, making part of this specification, in which similar letters indicate corresponding parts.

Figure 1 is a plan view.

Figure 2 is a longitudinal vertical section.

The circular meat-block has a rim, and rotates on a vertical axis upon the bench. It is rotated by means of cogs on its periphery, which are engaged by a spiral flange on a drum. This derives its motion by a band from the axis of the wheels whose cogs lift the spring arms. To these are attached the cleavers which cut the meat upon the rotating-block beneath.

In the drawings, A is the bench supported on legs B. C C are anti-friction rollers, which support the meat-block D, whose vertical axis d' has its journal in hole through the bench A. E is the rim of the cutting-block to keep the meat thereon while being cut. d d, &c., are cogs on the periphery of the block, projecting in a horizontal plane, and rotated by the spiral flange f on the drum F, which has its bearings in the standards G G which rise from the bench A. H is an axis revolved by cranks J J, and journalled by bearings at the upper end of the standards G G. It carries two wheels I I, with a number of cogs, i i, &c., which project from each face of the wheel, alternating with each other so as to raise the cleavers consecutively in their order. Fig. 1 shows the order to be in the rotation K K' K'' K'''. The pins P P above the axis H keep it in position, and a band, R, from the axis H to a drum or pulley on axis F rotates the latter and drives the cutting-block D through the medium of the spiral flange f and cogs d. The cleavers L are attached to their respective spring-arms, K K' K'' K''', by means of screw-rods M and nuts N, which admit of the adjustment of the cleavers so as to cause the edge to strike true on the plane of the block, and also to permit the adjustment of the cleavers as to length. The spring-arms K, &c., are made of tough and elastic wood, and are secured at their butt ends in a block, S, which is journalled in the standard T, which rises from the bench A. This hinging of the block S is for the purpose of adjusting the force of the blow of the cleavers upon the cutting-block, which is accomplished by the screw-rod W, whose lower end is hooked into the eye-bolt X, and the upper furnished with a nut, Y, and washer, Z. By screwing down the nut the block S is vibrated downwards and presses the edges of the cleavers more forcibly upon the cutting-block D, and of course giving them a more forcible blow upon the same when raised to a given height by the teeth i i. The pins V V secure the butt ends of the spring-arms K, &c., in the block S.

Having thus described my invention, what I claim as new, and desire to secure by Letters Patent, is—

The block S and spring-arms K, in combination with the screw-nut Y, and in the manner and for the purpose specified.

To the above specification of my improvement in meat-cutters I have set my hand this thirteenth day of February, 1867.

WM. M. MILLER.
